UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

DIRECTIVE ANTENNA SYSTEM.

Application filed June 27, 1925. Serial No. 39,919.

My invention relates to radio signalling systems, and particularly to antenna means operable therewith and capable of producing directive effects upon the signalling waves.

5 An object of my invention is to provide an antenna system having marked directive properties.

Another object of my invention is to provide an antenna system responsive to radio 10 waves in one direction.

Another object of my invention is to produce a multiple antenna system having a single tuning means.

Another object of my invention is to provide 15 a multiple antenna, and tuning means cooperating with a transfer means for a radio detector.

Another object of my invention is to provide 20 a receiving antenna which is less-responsive to static disturbances.

Another object of my invention is to provide 25 a radio antenna which is adapted for a radio relaying system.

In prior reception of radio signals, many 30 systems have been proposed for obtaining directional selectivity. These systems, have, however, been subject to various faults and inconveniences. A plurality of antennae has been set in a row, normal to the desired direction of the signal wave. Very many difficulties have, however, been experienced with such a system. As it is required that all of the antenna systems be tuned to the same oscillation frequency, elaborate provisions 35 have been necessary for accomplishing that result. The desired results have not been obtained because of the difficulty of tuning a large number of separate inductors to the same oscillation frequency.

40 My invention embodies a plurality of antenna devices positioned in a row and of substantially equal electrical characteristics. The system further embodied bridle wires connected to the antenna devices and to a single tuning coil in such way that the effective length of the bridle wires to the coil is substantially the same for each antenna system, thus securing a tuning means for all of the antenna systems which controls the frequency of all simultaneously and holds them at the same value. The interconnection provides a close coupling between the various circuits which causes them to oscillate at the same frequency, even though the structures 55 are slightly different and have slightly dif-

ferent separate resonant frequencies. My invention further provides a transfer line from the antenna system to a radio detector from which an audio frequency output may be conveyed to a broadcasting station.

Other objects and structural details of my invention will be apparent from the following description when read in connection with the accompanying drawings, wherein

60 Figure 1 is a diagrammatic view of circuits and apparatus comprising a preferred embodiment of my invention;

Fig. 2 is a curve showing the character of the direction selective effect of my antenna system; and

70 Fig. 3 is a diagrammatic representation of the antenna system and the received waves indicating the theoretical reason for the directive effect indicated in Fig. 2.

75 My invention embodies a group of antenna systems 1, 2, 3 and 4 which are preferably similar in size and construction. The antenna systems may consist of poles 5 to each of which is attached counterpoise conductor 6 consisting of a copper rod and an 80 aerial 7 consisting of another copper rod of substantially equal size. Both the aerials and the counterpoises are supported by insulators 8.

85 Additional poles 9 are placed near to apices of isosceles triangles formed upon a base line of pairs of the poles 5. Upon the poles 9 are mounted insulators 11 and 12. Bridle wires 14 are attached to the lower ends of the antenna structures 7 and supported upon the 90 insulators 12. Other bridle wires 15 are attached to the upper ends of the counterpoise structures 6 and supported upon the insulators 11.

95 Another pole 16 is provided which is positioned near the apex of an isosceles triangle formed upon the base line between the poles 9. Insulators 17 and 18 are attached to the pole 16 and bridle wires 19 and 20 are supported thereon, near the midpoint, and the 100 ends attached, as shown, to the bridle wires 14 and 15 at the points of support upon insulators 11 and 12. A tuning inductance 21 is supported upon the pole 16. Its terminals are connected to the bridle wires 19 and 20 at their midpoints upon the insulators 17 and 18. Lead wires 22 and 23 are attached to points upon the coil 21 as shown in Fig. 1. Additional poles 24 having cross arms 25 and 105 insulators 26 support the wires 22 and 23 for 110

connection to a radio detector apparatus 28 that may be located in a building 27.

Alternatively, the coil 21 may be omitted and the wires 22 and 23 may be connected directly to the wires 19 and 20. Changes in tuning are then conveniently made by variation of the inductance in the detector 28.

The audio-frequency output of the detector 28 may be conveyed by an ordinary metallic 10 transmission line 29 to a radio broadcasting station, or to such other apparatus as it is desired to energize by the audio-frequency currents.

In the operation of my device as a radio 15 receiving antenna, radio waves from a direction normal to the plane of the antenna systems will strike the various elements in zero-phase displacement and all will be set into oscillation simultaneously and in phase. The 20 oscillatory currents will flow between the aerials 7 and counterpoises 6 through the bridle wires 14 and 15, 19 and 20 and the inductor 21. Because of the construction 25 shown, the length of circuit of each antenna through the inductor 21 is substantially equal to that of all of the others and, therefore, since the antenna and counterpoise elements are also similar, the natural resonant frequencies are the same. The current flowing 30 in the coil 21 is then the result of energy picked up by the four antenna systems, and is in phase, and thus re-inforced.

The complete antenna system shows marked 35 directive properties, as indicated by the curve of Fig. 2. In this curve, the horizontal axis is indicated as the line through the various antenna structures. The pronounced directive quality then becomes evident from the shape of the curve.

The theoretical reason to be assigned for 40 this directive effect may be understood from an inspection of Fig. 3 in which the antenna and counterpoise systems are indicated by the circles 31, 32, 33 and 34. Sine waves 45 35, forming a wave front, are indicated as impinging upon the four antennae from a remote station, at an angle normal to the line of the antennae system. It will be obvious that the wave front strikes the four 50 antennae simultaneously and induces in them currents which are in phase, which currents, therefore, reinforce each other through the coil 21. Another sine-wave curve 36 is represented as traversing a line parallel to the 55 line of the antennae and it will be evident that the wave front strikes the antennae successively and that, therefore, when antenna 31 is energized to cause a current flow in one direction, antenna 34 is energized to cause 60 a current flow in the opposite direction. Likewise, when antenna 32 is energized to cause a current flow in one direction, antenna 33 is simultaneously energized to cause a current flow in the opposite direction. This is par-

ticularly the case if the separation of the end 65 antennae is the same as a wave length of the signal to which they are resonant, or an odd multiple thereof.

This property has been found particularly 70 convenient for the relaying of signals from an eastern point to a western point in the United States, since it has been found that the major portion of the troublesome static which tends to interfere with the relay signals, originates in or near the Gulf of Mexico 75 at a point almost due south of the receiving antenna systems. The received signals then come from a direction almost at 90° from the interfering static, this situation permits optimum utilization of the direction-selective 80 properties of the antenna system.

By means of the system of my invention, I 85 am enabled to provide a radio antenna system having marked direction selectivity and marked superiority for the reception of signal energy over the antenna of the prior art.

While I have shown but a single embodiment 90 of my invention, it is capable of various modifications and it is desired, therefore, that only such limitations shall be imposed thereon 95 as are required by the prior art or indicated in the appended claims.

I claim as my invention:

1. A radio antenna system comprising a 95 plurality of insulating supporting means linearly positioned, pairs of aerial and counterpoise members individually supported on respective supporting means, bridle wires connected thereto, insulating supports therefor and an inductor connected thereto.

2. A radio antenna system comprising a 100 plurality of insulating supporting means linearly positioned normal to the direction of signals, a plurality of pairs of aerial and counterpoise members, one pair being supported on each of said supporting means, bridle wires connected to said members, insulating supports therefor, and a single inductor connected thereto, a conveying circuit 105 connected thereto, and a radio-signal responsive means cooperating therewith.

3. A radio receiving arrangement, comprising a plurality of systems, each system comprising an aerial and an associated counterpoise, a plurality of pairs of bridle wires, the members of any one pair being connected to an aerial and its associated counterpoise, the bridle wires connected to aerials being connected together and thereby connecting conjugate points of the aerials, the bridle wires connected to counterpoises being connected together and thereby connecting conjugate points of the counterpoises and a tuning coil 115 connected to the bridle wires.

In testimony whereof, I have hereunto 120 subscribed my name this 4th day of June, 1925.

FRANK CONRAD.
